BRASSIERE DISPLAY DEVICES
Herb Coon, 1 Harbor Way, Kings Point, N.Y.
Filed Oct. 9, 1959, Ser. No. 845,514
3 Claims. (Cl. 223—68)

This invention relates generally to the field of display devices, and more particularly to an improved form thereof suitable for retail display of articles of clothing.

In the display of brassieres, it is often desirable to exhibit a plurality of different styles upon a form, so that the purchaser may have a realistic representation of the appearance of the brassiere when worn. Where brassieres are displayed upon complete mannequins, only one brassiere may be displayed on the same, and the remaining area on the mannequin is wasted, unless other types of garments are also displayed. While it is known in the art to provide mannequins showing only the pectoral portion of the body, such forms are not interconnectably stackable, so as to occupy a minimum of floor or counter area. Thus, the retailer must content himself with either a smaller display of fewer styles, or sacrifice valuable retail space.

It is therefore among the principal objects of the present invention to provide an improved brassiere display device which includes a plurality of readily interconnectable display elements, each of pectoral shape, and having means for selective interconnection with other similar units, whereby a complete display device of any desired number of elements may be quickly formed.

Another object of the invention lies in the provision of improved display structure of the class described, in which the individual display elements may be angularly disposed with respect to each other to provide a more attractive appearance and greater store area display coverage.

Still another object of the invention lies in the provision of a display device which may be formed substantially entirely by synthetic resinous injection molding techniques, whereby the same may be durable, long-lived, and possessed of resilient characteristics which may be employed to provide interconnecting means between the several display elements.

Still another object of the invention lies in the provision of a device of the class described in which the cost of fabrication may be of a reasonably low order with consequent wide sale, distribution and use.

A feature of the invention lies in the fact that no relatively moving parts are required in the fabrication of each of the individual display elements comprising the inventive device.

These objects and features, as well as other incidental ends and advantages, will more fully appear in the course of the following disclosure, and be pointed out in the appended claims.

In the drawing, to which reference will be made in the specification, similar reference characters have been employed to designate corresponding parts throughout the several views.

FIGURE 1 is a front elevational view of an embodiment of the invention.

FIGURE 2 is a side elevational view thereof.

FIGURE 3 is a vertical longitudinal sectional view as seen from the plane 3—3 in FIGURE 1.

FIGURE 4 is an enlarged fragmentary plan view showing the interconnection of two individual display elements.

FIGURE 5 is a fragmentary similar plan view showing the elements in fully interconnected condition, as might be seen from the plane 5—5 in FIGURE 3.

FIGURE 6 is an enlarged fragmentary rear elevational view as seen from the plane 6—6 in FIGURE 3.

2

FIGURE 7 is a perspective view corresponding to that seen in FIGURE 1, but showing the individual display elements in angularly oriented condition.

FIGURE 8 is a rear elevational view of one of the display elements.

FIGURE 9 is a bottom plan view thereof.

FIGURE 10 is a horizontal sectional view as seen from the plane 10—10 in FIGURE 8.

FIGURE 11 is a fragmentary enlarged sectional view as seen from the plane 11—11 in FIGURE 10.

FIGURE 12 is an enlarged fragmentary sectional view as seen from the plane 12—12 in FIGURE 7.

In accordance with the invention, the device, generally indicated by reference character 10, comprises broadly: a plurality of display elements 11, 12 and 13. Each of the elements 11 to 13 are substantially identical, and accordingly, a detailed description of one of said elements will serve equally well to describe the others. It is to be understood that more similar display elements may be added, if required, the limitation on the number being determined only by the limitations of the space in which the device is ultimately disposed.

The display element 11 is preferably molded integrally from synthetic resinous materials, and includes a neck portion 15, a main body portion 16 and a base portion 17. A suitable material for use in such molding is polystyrene, although other synthetic resinous materials of similar properties may be employed.

The neck portion 15 provides a quasi-circular attaching means 19 which includes a first horizontal annular member 20, a first vertical cylindrical member 21, a second horizontal annular member 22, a second vertical cylindrical member 23, and a top member 24.

The main body portion 16 is shaped to resemble the human form, and includes simulated shoulder portions 26, bust portions 28 and 29, and a display placket 30 which may be eliminated with corresponding loss of function, if desired.

The base portion 17 includes a horizontal reinforcing wall 31, and a pair of planar tongues 32 and 33. Reinforcing rib members 34 and 35 limit the degree of flexion of the tongue members 32 and 33. The tongue members form a semi-circular opening 36 rotatably engageable upon the cylindrical member 21, and normally maintained in fixed position through static frictional forces.

The device may be assembled as shown in FIGURES 1, 4 and 5, wherein the semi-circular edge 36 is slipped upon the groove formed by the cylindrical member 21 to assemble as many display elements 11—13 as desirable. Once interconnected, the individual elements may be angularly rotated about a vertical axis to the desired angle, and the assembled device 10 then stood up a horizontal surface (not shown) and allowed to lean against a corresponding vertical surface. From a consideration of FIGURE 2, it will be observed that the relative vertical position between the interconnecting parts is such that the assembled device will have a tendency to lean rearwardly, so that normally positive means interconnecting the device with supporting structure is not necessary.

I wish it to be understood that I do not consider the invention limited to the precise details of structure shown and set forth in this specification, for obvious modifications will occur to those skilled in the art to which the invention pertains.

65 I claim:

1. In a display device, a plurality of display elements each simulating a pectoral form including: a neck portion, a main body portion, and a base portion; each of said neck portions and base portions having directly mating interconnectable means thereon.

2. In a display device, a plurality of display elements

each simulating a pectoral form including: a neck portion and a main body portion; each of said neck portions having a groove therein, each of said base portions having a pair of planar tongues engageable within a groove in the neck portion of another of said plurality of display elements.

3. In a display device, a plurality of display elements each simulating a pectoral form including: a neck portion and a main body portion; each of said neck portions having a cylindrical groove therein, each of said base portions 10 having a pair of planar tongues defining a cylindrical edge

engageable within a groove in the neck portion of another of said plurality of display elements.
